REFRIGERATING SYSTEM

Emil Sieloff, St. Louis, Mo., assignor to Sieloff
Packing Company, St. Louis, Mo., a corpora-
tion of Missouri

Application February 16, 1933. Serial No. 656,983

5 Claims. (Cl. 261—116)

This invention relates to improvements in refrigerating systems, and consists of the novel construction hereinafter disclosed.

An object of the invention is to provide a refrigerating system for a cooler room, which system includes oppositely disposed units having parallel chambers in which air currents are inducted and educted for cooling the space therebetween, the air currents being contacted with refrigerating sprays in their passage through the refrigerating units.

Additional advantages of the invention will be apparent from the following detailed description taken in connection with the accompanying drawing, in which—

Fig. 1 is a plan view of a cooler room showing the system installed therein and taken substantially on the line 1—1 of Fig. 2.

Fig. 2 is a vertical section of the cooler room 20 and through the refrigerating units.

In the embodiment of the invention illustrated in the drawing, the refrigerating system is shown as installed in a cooling chamber or room 1 constructed in the usual manner with insulated walls. 25 The units are mounted against opposite vertical walls of the cooling chamber 1 and are arranged to direct the cooling currents of air toward the center of the chamber, driving the currents of air across the upper part of the chamber so that 30 the air currents will meet at approximately the center of the chamber and, by gravity, move downwardly in the chamber to cool the contents thereof.

Each of the units comprises a trough 2, preferably located on the floor of the chamber and having a discharge pipe 3 connected thereto so that the liquid accumulating in the trough 2 may be discharged to a recovery system. A back-wall 4 is positioned against an end wall of the 40 chamber 1, said wall having an out-turned portion 5 at its upper end. The wall 4 is preferably connected to and supported by the rear wall of the trough 2. A front wall 6 is supported by and connected to the front wall of the trough 2 and 45 extends upwardly, terminating at a distance below the ceiling of the cooling chamber. An intermediate wall 7 is positioned between the walls 4 and 6 and has an out-turned extension 8 that runs parallel with the portion 5 of the wall 4. 50 There are thus formed two parallel chambers 9 and 10, the chamber 9 having an inlet at its top between the upper edge of the wall 6 and the wall 8, and the chamber 10 having an outlet at its top between the walls 5 and 8.

55 It will be noted that the wall 7 terminates in

a plane across the top of the trough 2, so that the trough 2 provides an inter-communicating passage between the chambers 9 and 10. Inwardly extending and upwardly inclined from the wall 4 are a number of baffle walls 11 and, on the wall 7 60 and extending into the chamber 10 and intermediately spaced, are similar baffle walls 12, forming a tortuous passage for the outgoing current of air, the baffle walls serving to drop out moisture from the outwardly moving current of 65 air.

Within the trough 2 is a baffle comprising a downwardly inclined longitudinal wall 16 which extends from the rear edge of the trough, and a vertically disposed wall 17. This baffle serves to 70 prevent the splash from the sprays entering the lower end of the chamber 10, and thereby provides additional means for freeing the outgoing current of air from moisture.

Across the top of the chamber 9 and positioned 75 below the upper extremity of the wall 6 is a spray header 13 which is equipped with a plurality of spaced nozzles 14 directed downwardly into the chamber 9. The warmer currents of air are withdrawn from the chamber 1 by the siphoning 80 action set up by the plurality of sprays downwardly directed in the chamber 9. It will be understood that the sprays eject a refrigerating liquid such, for example, as cooled brine delivered to the header from a suitable source of supply 85 under pressure. The incoming air currents coming in contact with the spray are cooled and forced upwardly and outwardly through the chamber 10 into the cooling chamber. The liquid from the sprays is accumulated in the 90 trough 2, from which it is discharged and returned to the means employed for cooling the brine liquid. The outgoing current of air is freed from moisture by contacting with the baffles 11 and 12. The relatively dry cold air from the 95 cooling units is moved across the upper part of the cooling chamber and circulates downwardly in continuous air currents while the refrigerating units are in operation, thereby uniformly cooling the cooling chamber to the desired temperature. 100

In the construction of the unit, it is preferred that the chambers 9 and 10 shall be unobstructed longitudinally and closed only at the ends by walls 15; although, if it is desired, the unit may be made in sections by providing walls intermediate the walls 15.

I am aware that the invention may be modified in numerous particulars without departing from the spirit and scope thereof. I do not limit myself, therefore, to the exact construction 110

shown and described, but what I claim and desire to secure by Letters Patent is:—

1. A refrigerating system for a cooling chamber comprising oppositely spaced refrigerating units, each including a trough extending across the cooling chamber and positioned adjacent to one wall thereof and to the floor of said chamber, three spaced walls forming longitudinal parallel chambers the outer one of which is provided 10 with an inlet opening in the side thereof and the inner one of which is provided with an outlet opening above said inlet opening and adjacent to the ceiling of the cooling chamber, a spray header extending longitudinally of the upper part of the outer chamber, and a plurality of sprays supported by said header and directed downwardly.
2. A refrigerating system for a cooling chamber comprising oppositely spaced refrigerating units, each including a trough extending across the cooling chamber and positioned adjacent to one wall thereof and to the floor of said chamber, three spaced walls forming longitudinal parallel chambers the outer one of which is provided with 20 an inlet opening in the side thereof and the inner one of which is provided with an outlet opening above said inlet opening and adjacent to the ceiling of the cooling chamber, a spray header extending longitudinally of the upper part of the outer chamber, a plurality of sprays supported 30 by said header and directed downwardly, and a plurality of upwardly directed and inwardly inclined baffle walls arranged in said inner chamber.
3. A refrigerating unit comprising a longitudinal trough, a wall extending upwardly from one longitudinal wall of said trough and a wall 35 extending upwardly from the other longitudinal wall of said trough, said last named wall having an over-turned and outwardly directed extension terminating at a distance above the upper edge of said first named wall, an intermediate wall extending between said two first named walls, said intermediate wall terminating at its lower 40 extremity above the upper edge of the trough and

having an out-turned upper extremity arranged parallel with the extremity of said second named wall, and spray equipment located between said first named wall and said intermediate wall having downwardly directed jets.

4. A refrigerating unit comprising a longitudinal trough, a wall extending upwardly from one longitudinal wall of said trough and a wall extending upwardly from the other longitudinal wall of said trough, said last named wall having an over-turned and outwardly directed extension terminating at a distance above the upper edge of said first named wall, an intermediate wall extending between said two first named walls, said intermediate wall terminating at its lower extremity above the upper edge of the trough and having an out-turned upper extremity arranged parallel with the extremity of said second named wall, spray equipment located between said first named wall and said intermediate wall having downwardly directed jets, and baffle walls carried by the intermediate wall and said second named wall.

5. A refrigerating unit comprising a longitudinal trough, a wall extending upwardly from one longitudinal wall of said trough and a wall extending upwardly from the other longitudinal wall of said trough, said last named wall having an over-turned and outwardly directed extension terminating at a distance above the upper edge of said first named wall, an intermediate wall extending between said two first named walls, said intermediate wall terminating at its lower extremity above the upper edge of the trough and having an out-turned upper extremity arranged parallel with the extremity of said second named wall, spray equipment located between said first named wall and said intermediate wall having downwardly directed jets, and a baffle comprising a downwardly extending wall from the rear wall of the trough and a vertical wall in extension thereof terminating above the lower wall of the trough.
